UNITED STATES PATENT OFFICE.

COLBY B. CHENAULT, OF NASHVILLE, TENNESSEE.

SPRING BED.

Application filed October 2, 1922. Serial No. 591,835.

To all whom it may concern:

Be it known that I, COLBY B. CHENAULT, a citizen of the United States, residing at Nashville, in the county of Davidson and 5 State of Tennessee, have invented certain new and useful Improvements in Spring Beds, of which the following is a specification.

This invention relates to spring beds and 10 its primary object is to provide improved and efficient means whereby weight placed upon the spring mattress or bed bottom may be equalized and sagging of the said mattress or bed bottom at one side will be prevented. Another object of the invention is 15 to provide improved means for supporting the equalizing members, and also to provide novel means for maintaining the supporting springs in fixed positions. Another object 20 of the invention is to provide means whereby the head and foot frames may be brought into a compact position against the mattress supporting frame to facilitate storage and transportation of the bed, and the invention 25 seeks to improve generally the construction of a bed to increase the efficiency, durability and strength of the same without increase in the cost of manufacture. All these stated objects, and other objects which will inci- 30 dentally appear in the course of the following description, are attained in a structure such as that illustrated in the accompanying drawings, and the invention resides in cer- 35 tain novel features which will be particularly pointed out in the appended claims.

In the drawings—

Figure 1 is a side elevation, with some 40 of the parts broken away, of a bed embodying my present improvements;

Fig. 2 is a transverse section on the line 2—2 of Fig. 1;

Fig. 3 is an enlarged perspective view 45 showing the means for supporting the equalizing levers and retaining the supporting springs in position;

Fig. 4 is an enlarged perspective view of a bracket which is employed to support the ends of the side bars of the bed bottom;

Figs. 5 and 6 are detail perspective views 50 of the clips which secure the base of the bed bottom supporting springs;

Fig. 7 is a detail perspective view of the device for securing the upper end of the said supporting spring, and

Fig. 8 is a detail perspective view showing 55 a form of support especially designed for at-

taching the bed bottom to a wooden bed frame.

The bedstead comprises a head frame 1, a foot frame 2, and an intermediate bed bottom-supporting frame 3. The said frame 3 consists of side bars and end bars rigidly connecting the side bars, all said members being constructed of angle iron, as shown and as will be readily understood. To connect the said intermediate supporting frame 3 with the head and foot frames, I employ links 4 which are pivoted to the side bars of the frame 3 and also to the head and foot frames, respectively, near the lower ends of 70 the sides thereof whereby, when the bed is set up for use, these links will assume a diagonal or inclined position and will act as braces to prevent collapse of the bed. This position is shown in full lines in Fig. 75 1. I also employ upper shorter links 5 which are each pivoted at one end to the head or foot frame, as the case may be, and at its opposite end to the adjacent side bar of the intermediate frame 3. Stop lugs 6 of 80 any convenient or preferred form are provided on the sides of the frame 3 above the links 5 so that the upward movement of the links will be prevented and the pivotal connections at the ends of these links are so disposed that, when the bed is set up, these links will lie in horizontal planes approximately coincident with the lower edges of the side bars. The lugs 6 prevent relative 85 downward movement of the intermediate frame 3 inasmuch as they rest upon the upper edges of the link 5 when the bed is set up, as clearly shown in Fig. 1, and therefore, when the bed is set up it will be firm and steady and may be used freely without 90 any fear of collapse. At the same time the head and foot frames may be readily folded into positions below the intermediate frame 3, as shown by dotted lines in Fig. 1, and to accomplish this result, it is necessary 100 merely to swing the respective frames inwardly at their lower ends so that the said lower ends will extend under and be brought close to the frame 3. This foldability of the bed frame is especially advantageous when 105 a large number of the beds are to be stored or transported.

Extending across the ends of the intermediate frame 3 are rails 7 which are preferably of angle iron, as shown clearly in 110 Fig. 3, the extremities of the horizontal webs or flanges of these rails being turned down-

wardly and rigidly secured to the outer sides of the sides of the frame 3, as shown at 8. The rails will thus be secured to the supporting frame 3 and will rest directly thereon so that a very rigid and strong support for the equalizing levers and the bed bottom will be furnished. The vertical webs of the rails are connected at intervals by bolts 9 and around the said bolts are fitted spacer sleeves 10 whereby the rails will be held rigidly in their proper spaced relation. By referring more particularly to Fig. 2, it will be noted that the connecting bolts 9 are provided at the ends of the rails 7 and at points between the ends and the center thereof. The inner bolts constitute fulcrums for the equalizing levers 11 which are engaged upon said bolts between the rails and arranged parallel therewith, the outer ends of the said levers extending upwardly, as shown at 12, and the inner ends thereof being connected by links 13, it being noted that the inner ends of the levers overlap and the links 13 are disposed normally upon vertical lines. To maintain the levers centrally between the rails 7, I provide a spacing sleeve or collar 14 at each side of each lever upon the bolt constituting the fulcrum of the same. To the outer ends of the equalizing levers, I pivotally connect the lower ends of links 15 which have their upper ends pivoted to a lug 16 extending laterally from a bracket 17 which provides means for securing the ends of the side brace bar 18 and also means for supporting the said bars and the bed bottom upon the supporting springs 19. The springs 19 are preferably conical helical springs having their bases or lower ends resting upon the rails 7 and their upper ends disposed below and connected with the brackets 17, one of the springs 19 being provided at each corner of the frame 3. To secure the bases of the springs 19 in fixed position upon the rails, I provide clips 20 which are secured rigidly against the side of one rail 7 adjacent the end thereof and consists of flat plates having overhanging lips 21 at their upper ends which are adapted to engage over the coil of the spring. As shown clearly in Figs. 1 and 3, the clip extends upwardly at the inner side of the base or lowest coil of the spring and the lip 21 projects outwardly over the said coil so as to firmly engage the same and hold it to the rail. The clip 20 is provided upon the inner rail 7, and upon the outer rail 7 I secure the clip 22 which also consists of a flat plate secured against the vertical web of the adjacent rail but is wider than the previously described clip and is provided at its upper edge with an overhanging elongated lip 23 extending beyond the ends of the plate, as clearly shown. The projecting ends of the elongated lip 23 will extend over the lowest coil of the spring 19, as shown in

Fig. 3, so as to bear firmly upon the upper side of the same and clamp it against the upper edge of the rail. The base of the spring is thus secured positively against the supporting rails at three spaced points and shifting of the spring upon the rail is positively and effectually prevented. It will be readily noted that the clips 20 and 22 are secured to the rails by the same bolts which hold the rails in fixed relation. At the upper end of each spring 19, I employ the attaching block or clamp 24 shown in detail in Fig. 7. This block consists of a hub or cylindrical central member 25 and an annular flange or rib 26 at the lower end of said hub, the said flange or rib having a passage 27 formed therethrough at an angle to the radius of the hub so that the opposed walls of said passage will assume a spiral formation and be adapted to closely engage the upper terminal coil of the spring 19. A securing bolt 28 is inserted upwardly through the hub 25 and through a lateral lug 29 upon the bracket 17, and a nut 30 is turned home upon the bolt against the said lug 29 so as to clamp the bracket against the under side of the lug. It will be readily noted that the lugs 16 and 29 are at opposite sides of the body of the bracket 17 so that the links 15 and the lever 11 will be alined transversely of the bed with the supporting springs 19. The bracket 17 is provided at its outer end with a head 31 which is adapted to fit against the end bar 32 of the bed bottom and be rigidly bolted thereto. The inner end of the bracket is extended downwardly, as shown at 33, and has an eye 34 formed at its extremity. This eye 34 receives the end of the side bar 18 which is preferably tubular, so as to possess the required strength without excessive weight, and forms a rigid brace to maintain the alined brackets 17 at the head and foot of the bed in rigid spaced relation. The end bars 32 extend transversely of the bed and constitute the end members of the bed bottom. To the said bars 32, I attach transverse series of contractile springs 35, the inner ends of said springs being engaged with the end bars of a rigid rectangular frame 36 which carries and supports a fabric, indicated at 37, which may be of coiled springs or loosely connected links or any other well-known material commonly employed for bed bottoms. To reinforce this bed bottom and maintain the central portion of the same in the same plane with its ends, I provide a central yieldable support consisting of helical springs 38 secured at their lower ends upon a supporting or base frame 39 and having their upper ends engaged with or secured to transverse bars 40 which extend across the bed bottom at the center thereof. Suspending rods 41 are secured at their centers to the frame 39.

and at their ends to the end bars 32 so that the frame 39 will be supported in fixed relation to the bed bottom, but the springs 38 will permit the center of the bed bottom to 5 yield to weight imposed thereon but will immediately return the bed bottom to its normal place after it has been relieved of the weight. I thus prevent excessive permanent sagging of the bed bottom while permitting the central portion of the same to 10 yield to the weight of the person or persons reclining upon the bed.

The construction which has been described is intended more particularly for use in connection with metal beds. The spring-supporting structure, however, may be used upon wooden bedsteads and, in Fig. 8, I have illustrated one slight modification of the supporting structure which will be found 15 advantageous in applying the device to a wooden bedstead. In said figure, the reference numerals 42 indicate rails which are to be substituted for the rails 7 and support the equalizing levers. The ends of these rails 20 are turned upwardly, as shown at 43, to provide short posts and in and between the upper extremities of these posts, I pivotally mount a hook or bracket 44, the said hook or bracket being constructed with an eye or 25 sleeve 45 through which and the ends of the posts an attaching bolt 46 is inserted. This bolt 46 also serves to connect the posts 43 and a stop pin 47 is fitted in the post between 30 the upper extremities of the same to prevent the hook or bracket 44 being swung inwardly 35 beyond a predetermined point. When the device is to be applied to a wooden bedstead, the hooks 44 are engaged over the wooden side rails, indicated at 48, as shown in full 40 lines in Fig. 8, the remaining portions of the apparatus being exactly the same as illustrated in the other figures of the drawings and hereinbefore fully described. When the device is to be shipped or to be 45 set aside, the hook brackets 44 are released from the bed rails and may be swung downwardly, as indicated by dotted lines in Fig. 8, to positions between the posts 43 and between the ends of the rails 42, as will be 50 readily understood.

In the use of a bed embodying my present improvements, the usual mattress is placed upon the bed bottom 37 and the weight imposed thereon is carried by the springs 19, 55 as will be obvious. The bed bottom will readily flex and conform to the position assumed by the sleeper so that it will be entirely comfortable in all positions of the user. Should the weight be shifted to one 60 side of the bed bottom, the springs 19 at that side will, of course, be compressed so that the adjacent side bar 18 and the brackets 17 carrying the same will be lowered. The descending movement of the brackets 65 will, however, be imparted directly to the

adjacent equalizing levers 11 through the links 15 so that the upper ends of said levers will swing downwardly and the inner ends of the same upwardly. Inasmuch as the inner ends of the levers at one side of the bed 70 are connected by links 13 with the inner ends of the equalizing levers at the opposite side of the bed, the movement of one set will be transmitted in both kind and extent to the opposite set of levers and, consequently, 75 the unoccupied side of the bed will be lowered in exactly the same degree as the side receiving the weight. Distortion of the bed is thus prevented and the life of the bed bottom is prolonged. The means employed 80 for securing the supporting springs in place effectually and positively retain them in the positions in which they may be located so that the bed bottom will be supported in a level position and the leverage exerted by 85 the moving parts will be uniform at all points. It will be understood that the side bars 18 are rigidly secured in the brackets 17 by brazing, welding, or by any other preferred means and the said brackets 17 furnish 90 a very strong and rigid connection between the said side bars and the end bars of the bed bottom as well as means for attaching and maintaining the proper relation of the supporting springs and the links 95 connected with the equalizing levers.

Having thus described the invention, what is claimed as new is:

1. In a bed, the combination of a supporting frame, rails secured transversely upon said frame, conical helical springs having their wider ends resting upon and bridging said rails, means for securing said ends of the springs rigidly to the rails, a bed bottom, means for connecting the bed bottom with the upper ends of the said springs, equalizing levers fulcrumed upon the rails, means for coupling the inner ends of the equalizing levers whereby they will have similar movement, and means for connecting 100 the outer ends of the equalizing levers with the bed bottom at points spaced inwardly from the springs.

2. In a bed, the combination of a supporting frame, rails secured on said frame at the 115 ends thereof, a bed bottom arranged above said supporting frame, supporting springs secured upon said rails at the ends thereof, brackets secured to and depending from the said bed bottom, means for securing the upper ends of the springs to the outer sides of said brackets; a side bar rigidly secured in and extending between the lower ends of the brackets at one side of the bed bottom, equalizing levers carried by the rails, and links 120 connecting the outer ends of said equalizing levers with the inner sides of the said brackets.

3. In a bed, the combination of a supporting frame, springs mounted on said frame at 125

the corners thereof, a bed bottom disposed above said frame, brackets secured to the under side of the bed bottom and having laterally projecting lugs on their outer sides, 5 spring attaching hubs secured to the under sides of said lugs and constructed to fit within the uppermost coil of the adjacent spring and engage and retain the extremity of said coil, equalizing levers disposed below the 10 bed bottom and having their inner ends connected for equal movement, and links connecting the outer ends of said levers with the inner sides of the said brackets.

4. In a bed, the combination of a supporting frame, transverse rails secured on said frame at the ends thereof, springs secured upon the rails at the ends of the same, a bed 15

bottom arranged above the supporting frame and the springs, brackets provided at their outer ends with heads secured rigidly to the 20 ends of the bed bottom and having their inner ends extending downwardly, side bars secured to and extending between the lower inner ends of the brackets at the same side of the bed bottom, lugs projecting laterally from the opposite sides of the upper portions of the brackets, means for securing the upper ends of the springs to the lugs on the outer sides of the brackets, equalizing levers carried by the rails, and links connecting the outer ends of the levers with the 25 lugs on the inner sides of the brackets.

In testimony whereof I affix my signature.
COLBY B. CHENAULT. [L.S.]
